UNITED STATES PATENT OFFICE.

RAMEY McALISTER, OF WASHBURN, TEXAS.

GARMENT-HANGER.

1,242,829.

Specification of Letters Patent.

Patented Oct. 9, 1917.

Application filed January 23, 1917. Serial No. 143,997.

To all whom it may concern:

Be it known that I, RAMEY McALISTER, a citizen of the United States, residing at Washburn, in the county of Armstrong and State of Texas, have invented new and useful Improvements in Garment-Hangers, of which the following is a specification.

This invention relates to a garment hanger which may be employed as a support for either men's or women's wearing apparel when not in use.

The primary object of the invention is to provide a hanger of this character which is adjustable to enable the hanger to be used in connection with garments of different sizes and is so constructed that an entire suit of clothing may be connected therewith and supported thereby in such a manner as to insure the wrinkles being removed from the garments when disconnected from the hanger.

Another object of the invention is to provide a hanger of this character which is so constructed as to enable the garments when connected therewith to be creased in the proper places and is particularly serviceable for this purpose when used in connection with trousers, coats, and the like.

With these and other objects in view, the invention resides in the novel combination and arrangement of parts, which will be hereinafter described and particularly pointed out in the claims.

The preferred embodiment of the invention has been illustrated in the accompanying drawings, although no restriction is necessarily made to the precise details of construction therein shown, as changes, alterations, and modifications, within the scope of the claims may be resorted to when desired.

In the drawings:

Figure 1 is a front elevation of a garment hanger constructed in accordance with the invention.

Fig. 2 is a rear elevation of the same.

Fig. 3 is a horizontal transverse section on the line 3—3 of Fig. 1.

Fig. 4 is a detail perspective view of one of the clamps and showing the same removed from the hanger.

Fig. 5 is a detail sectional view through one of the clamps and showing the same held in open position.

55 Like characters of reference denote corre-

sponding parts throughout the several views in the drawings.

Referring now to the drawings in detail, the letter A designates a garment hanger constructed in accordance with the invention and having a plurality of spaced and horizontally extending cross strips 5 curved for a portion of their length adjacent their ends. The strips 5 are formed from resilient material and have arranged thereon a pair 60 of spaced and vertically extending bars 6 and 7.

The bar 6 is rigidly secured to the cross strips 5, while the bar 7 has secured to the rear face thereof spaced and resilient 70 tongues 8 between which and the bar pass the cross strips 5, said bar being retained upon the strips by loops 9 having pivotal connection with the bar and engaging the free ends of the tongues 8.

Each tongue 8 has formed thereon a rib 10, which when the tongue is engaged by a loop 9 on the bar 7 is received within a groove 11 in the back of the strip 5 whereby, the bar 7 is normally locked against longitudinal movement on the strips 5, but may be moved longitudinally of said bars when the occasion requires by releasing the loops 75 from the tongues 8.

Supplemental bars 12 and 13 extend transversely of the strips 5 adjacent the ends thereof with the bar 12 which is arranged in spaced relation to the bar 6 rigidly connected with the strips, while the bar 13 is slidably connected with said strips by 80 means of tongues 14 and loops 15 corresponding in construction and arrangement to the loops and tongues on the bar 7.

A pair of auxiliary bars 16 and 17 which are of less length than the bars 6 and 7 are 85 held in contact therewith by springs 18, the arms 19, of which are crossed and have their free ends connected with the bars to hold the same in contacting relation, whereby the auxiliary bars 16 and 17 coact with 100 the bars 6 and 7 in providing the garment hanger with main clamps by means of which a skirt or a pair of trousers may be creased when connected with the hanger.

One of the springs 18 connected with each 105 of the main clamps is provided with a prop leg 17' by means of which the clamps may be held in open position, while each of the bars 6 and 7 included in the main clamps have secured thereto above the strips 5, a 110

spring clip 17" which may be engaged with the band of a pair of trousers or the band of a skirt when either of these garments is to be connected with the hanger.

- 5 Each of the supplemental bars 12 and 13 has arranged thereon an auxiliary bar 20 normally held in contact with the supplemental bar upon which it is arranged by springs 21 similar in construction to the 10 springs 18 and enable the auxiliary bars 20 to act in conjunction with the bars 12 and 13 in providing the hanger with a pair of supplemental clamps which may be engaged with the sides of a garment, such as 15 a coat, or the like to crease the same in the proper places and to hold the garment in such position upon the hanger that the wrinkles will be removed therefrom when removed from the hanger.
- 20 One of the springs 21 connected with each supplemental clamp is provided with a prop leg 21' which is pivotally connected with one arm of the spring whereby the prop leg when engaged with the other arm 25 of the spring as shown in Fig. 5 in the drawing enables the supplemental clamps to be held in open position to facilitate the insertion between the bars comprising the clamp of the portion of the garment to be 30 creased.

The main bars 6 and 7 have secured thereto the terminals of a flexible attaching member 22 with which is swingingly connected a curved supporting bar 24 which may be 35 arranged within a coat, waist, or the like, when the hanger is in use.

When it is desired to use the hanger as a support for a suit of clothing, the main and supplemental clamps may be held in 40 open position by means of the prop legs 17' and 21' and the trousers, or skirt as the case may be, folded in the usual manner and connected with the hanger by the clips 17", with the portion of the garment to be 45 creased arranged between the bars forming the main clamps.

The coat, or waist, is now arranged on the bar 24 with the sides of the garment passing between the bars including the supplemental clamps of the hanger, after 50 which, the prop legs are moved to a position to permit the clamps to firmly engage the garments and crease the same in the proper places.

55 Through the provision of the tongues and loops on the bars included in the clamp sec-

tions, it will be seen that a clamp in each pair of clamps may be adjusted longitudinally of the strips 5 to insure the garment being properly stretched to remove the 60 wrinkles therefrom and also permitting the hangers to be used in connection with garments of different sizes.

From the foregoing description, taken in connection with the accompanying drawings, it is at once apparent that a garment hanger has been provided which though comparatively inexpensive of manufacture, is highly efficient for the purpose set forth.

Having thus described the invention, what is claimed as new, is:

1. A garment hanger comprising resilient cross strips curved for a portion of their length adjacent their ends, spaced pairs of vertically extending bars, springs having 75 crossed arms connected with the respective bars in each pair of bars, a bar in some of said pair of bars rigidly connected with said strip, tongues on a bar in the other pairs of bars firmly bearing against said 80 strips, and prop legs pivotally connected with one of the arms of some of said springs and engageable with the other arm thereof.

2. A garment hanger comprising spaced pairs of clamps, cross strips rigidly connected with a clamp in each pair of clamps, tongues on the other clamp in each pair of clamps engageable with said strips and slidably connecting the last mentioned clamps therewith, means engageable with said 90 tongues to lock the last mentioned clamps against sliding movement on the strips, an attaching member connecting a pair of said clamps, and a supporting bar carried by the attaching member.

95 3. A garment hanger comprising spaced pairs of bars, supporting strips rigidly connected with a bar in each pair of bars and having grooves therein, tongues on a bar in each pair of bars slidably connecting the 100 same with said strips, locking ribs on said tongues engageable with said grooves, loops on the last mentioned bars engageable with the tongues to hold said ribs in said grooves, auxiliary bars, springs having connection 105 with the auxiliary bars and the pairs of bars for holding the auxiliary bars in engagement therewith, an attaching member connecting a pair of said bars, and a supporting bar carried by the attaching member.

110 In testimony whereof I affix my signature.

RAMEY McALISTER.
